UNITED STATES PATENT OFFICE.

THOMAS JOHN CAHILL, OF PATTERSON, CALIFORNIA.

WALL CONSTRUCTION.

1,100,531.

Specification of Letters Patent. Patented June 16, 1914.

Application filed August 14, 1913. Serial No. 784,703.

To all whom it may concern:

Be it known that I, THOMAS J. CAHILL, a citizen of Australia, and a resident of Patterson, in the county of Stanislaus and State 5 of California, have invented a new and Improved Wall Construction, of which the following is a full, clear, and exact description.

My invention relates to concrete wall construction, and objects of the invention are to 10 construct a concrete wall having a degree of elasticity not less than that of brick walls, and a wall in which no cracks extending through the wall can be produced.

In my improved construction separate and 15 distinct blocks are molded *in situ* in successive layers, to break joint as in walls built of previously formed blocks. In connection with the blocks, metallic joint members, preferably of sheet metal are employed and 20 molded in place in the molding of the successive layers of the blocks, there being horizontal and vertical joint members co-extensive with the adjacent surfaces of the blocks at the joints. The joint members form part 25 of the mold and are so shaped as to cause interlocking of adjacent blocks.

The invention will be particularly explained in the specific description following.

30 Reference is to be had to the accompanying drawings forming a part of this specification, in which similar characters of reference indicate corresponding parts in all the figures.

35 Figure 1 is a longitudinal vertical section of a section of wall embodying my invention together with the exterior mold members, the section being taken on the line 1—1 of Fig. 2; Fig. 2 is a transverse vertical section, 40 the section being taken on the line 2—2 of Fig. 1; Fig. 3 is a perspective view of a portion of one of the horizontal joint elements; and Fig. 4 is a perspective view of one of the 45 vertical joint elements.

50 In producing a wall in accordance with my invention a mold is formed to permit the pouring and molding of the material to form the bottom or the first layer of blocks 10. The outer members of the mold consist 55 of sides 11 formed, in practice, of planks or the like. Before pouring the concrete for forming the blocks 10, vertical joint members 15 are so disposed as to separate the blocks and to form transverse members of the mold, said vertical joint members having lateral flanges 16 which are nailed to the

inner faces of the sides 11 of the mold. The material having been poured horizontal joint members 12 are laid on the blocks and are fastened to the inner faces of the sides 60 11 of the mold through the medium of vertical flanges 14 on the said joint members, suitable nails being driven through the flanges into the sides 11. The horizontal joint members 12 are formed with longitudinal 65 concavo-convex ribs 13 to form grooves in the blocks at the under side of the said members. The said ribs will also form longitudinal tongues on the under side of the next layer of blocks. The vertical joint 70 members 15 are formed, on the top and bottom edges respectively, with depressions 17 and lugs 18 corresponding with the ribs 13 so that the horizontal joint members 12 may take a firm seat on the vertical members 15. 75 The first layer of blocks having been thus completed with their horizontal and vertical joint members 12 and 15, the next upper series of vertical members 15 are secured to the inner faces of the sides 11 of the mold 80 through the medium of the lateral flanges 16, said vertical joint members being disposed intermediate the lower series of vertical joint members so that the second layer of blocks 10 will break joint with those below. The material for the second series of 85 blocks is now poured and at the proper time the next horizontal joint members 12 are laid on top of the blocks and fastened to the sides 11 of the mold. The forming of successive blocks will thus produce longitudinal 90 tongues 19 on blocks of one layer and corresponding and alined grooves 20 in the opposite faces of the blocks. Thus the joint members and the blocks will be interlocked with 95 one another and the blocks will be separately formed. The wall now having been completed to the proper height the sides 11 of the mold are removed and preferably the flanges 14 and 16 of the joint members are 100 stripped or cut off leaving the joint members co-extensive with the adjacent faces of adjacent blocks. A plaster coat is laid on the faces of the wall and the joints may have the usual markings after the manner of 105 brickwork or other block work.

Having thus described my invention, I claim as new and desire to secure by Letters Patent:

1. A concrete wall composed of blocks, 110 and joint elements in vertical and horizontal joints, said joint elements being co-ex-

tensive with the adjacent surfaces of the blocks, the horizontal joint elements having concavo-convex ribs, the blocks having tongues and grooves corresponding to the said ribs, and the vertical joint elements having at the top and bottom edges, respectively, recesses and lugs corresponding with the said ribs.

2. A concrete wall composed of separate blocks molded *in situ*, horizontal and vertical joint members substantially co-extensive with the adjacent surfaces of the blocks and

molded between the latter, said joint members having engaging or interlocking means, and provided with side flanges for holding the detachable molding elements applied on the sides of the wall, as described. 15

In testimony whereof I have signed my name to this specification in the presence of two subscribing witnesses.

THOMAS JOHN CAHILL.
